UNITED STATES PATENT OFFICE.

HORATIO G. GILLMOR, OF WASHINGTON, DISTRICT OF COLUMBIA.

RAIL-ANCHOR.

1,205,945.

Specification of Letters Patent. Patented Nov. 21, 1916.

Application filed May 24, 1915. Serial No. 29,952.

To all whom it may concern:

Be it known that I, HORATIO G. GILLMOR, a citizen of the United States, residing at Washington, in the District of Columbia, 5 have invented a new and useful Improvement in Rail-Anchors, of which the following is a specification accompanied by drawings.

This invention relates to devices known 10 as rail anchors, anticreepers or rail stays and one of its objects is to form a simple device which will prevent the longitudinal movement of the rails of railways.

Another object is to provide against rendering the device inoperative by reverse 15 movement of the rail or by the effect of vibration.

To the accomplishment of these objects and such others as may hereinafter appear, 20 as will be readily understood by those skilled in the art, the invention comprises a rail anchor embodying the features of construction, the combination of elements and arrangement of parts having the general mode 25 of operation as hereinafter described and claimed.

The preferred embodiment of the invention is shown in the accompanying drawings, in which:—

Figures 1, 2 and 3 are, respectively, a bottom view, a section at the plane indicated by X X in Fig. 1 and a side elevation, 30 showing the device in operative position on the rail. Figs. 4 and 5 show two positions 35 of the parts in the course of the application of the device. Fig. 6 is a view of the cross bar and Fig. 7 a view of the tie engaging key.

Similar letters refer to similar parts 40 throughout the several views.

In the embodiment of the invention illustrated in the drawings A is the rail, B a cross tie, C a rail base engaging cross bar and D a tie engaging key. The cross bar 45 has a jaw E at one end formed by overturning a portion F of the end of the bar. This jaw is so arranged as to permit the cross bar to be readily placed in position and with this purpose the portion G of the bar is set at an angle to the body of the bar. The other end of the bar is turned up at H to form a shoulder surface I a portion of 50 which will engage with the edge of the rail base. This end has also the curved surface K. The tie engaging key D has a hook portion L with surfaces M which engage the

upper surface of the rail base and surfaces N which engage the surface I of the cross bar C when the device is in operative position. The key D is recessed at O to receive 55 the portion H of the cross bar C and the sides P of this recess flare so that they do not contact with the sides of H except near the bottom of the recess O, so that the cross bar may move angularly without producing 60 corresponding angular movement of the key D. The key D is also provided with curved surfaces Q adapted to engage the curved surfaces K of the cross bar and to coat with these surfaces. The sides of the hook portion L of the key D are cut up as at R to provide relatively short bearing of the surfaces M upon the rail base so that key D may cant on the rail base. Key D is also provided with two tie engaging portions 75 S and T either of which may lie against the tie.

To apply the device the cross bar C is placed in position on the rail. Fig. 4 illustrates one position of the bar in being placed 80 and it will readily be understood that the bar is so formed that the point of the portion I will just pass clear of the edge of the rail base when the other side of the base flange is engaged between the point of the 85 portion F and the surface G of the other end of the cross bar C. In some cases it may be necessary to tap the cross bar gently with a hammer to reach this position. When the arm H clears the edge of the rail base it 90 is drawn upward into the position illustrated in Fig. 5 and in this position the cross bar fulcrums at U on the bottom of the rail base. The key D is then placed in the position illustrated in Fig. 5 with the surfaces 95 M and N engaging with the upper surface of the base flange of the rail and the surface I of the portion H of the cross bar C. In this position the surfaces Q of key D will just begin to engage with the surfaces K on the lower portion of the cross bar. The key is then driven to the final position illustrated in Fig. 2 and in reaching this position rotates or moves angularly with the surfaces M and N engaging with the upper surface of the rail base and the arm H. This forced movement of the key D draws the cross bar C into contact with the rail bottom and presses it strongly upward 105 against the rail bottom.

The direction in which the rail tends normally to move is indicated by the arrow in

Fig. 3 and this direction will be referred to as forward and the reverse direction as backward. Since the rail base is gripped between surfaces F and U at one side of the rail and the other end of the cross bar C is held in the key D by engagement of the portion H with the bottom portions of the sides P of the recess O, when the rail moves forward under the creeping stresses it carries surfaces F and U with it and the cross bar assumes a position at an angle to its original position as indicated by the dotted lines in Fig. 1. The drawing of the surfaces I of the portion H of the cross bar C into contact with the rail base edge by the forcing of the key D into position has caused the rail to be gripped between the surface I of portion H and the surface V at the bottom of the jaw at the other end of the cross bar. The angular movement or skewing of the cross bar C will increase the grip of the cross bar C upon the rail. The resistance of the device to further creeping movement is thus increased automatically by this movement of the cross bar. The key D is held by the contact of the tie engaging portion S with the face of the cross tie and the pressure transmitted through key D sets up a moment tending to turn or cant key D slightly on the rail. The surface M in contact with the rail is relatively short longitudinally of the rail so that the moment thus set up causes the key D to cant slightly as indicated by the dotted lines in Fig. 3. This action increases the vertical pressure, produced by the key, of the cross bar C upwardly upon the rail bottom and therefore still further increases the resistance of the device to further movement of the rail in the forward direction. This action continues until the resistance to forward movement is equal to the forces tending to produce forward movement and generally a very slight forward movement of the rail will be sufficient to make the grip of the device upon the rail sufficient to withstand all the forces tending to move the rail forward.

If the rail through temperature changes moves in the backward direction the first effect will be to carry portion S out of contact with the face of the tie. If the key should be held in the ballast there might be some angular movement of the cross bar upon the rail base but the cross bar would continue to grip the rail between surfaces F and G so that whenever movement in the forward direction again occurred the gripping action of the device would again become effective. The engagement of the key D with the cross bar and rail will readily be seen to be such that the tightness of the key D cannot be effected by vibration or other accidental causes.

Obviously some features of the invention may be used without others and the inven-

tion may be embodied in widely varying forms, within the skill of the artisan.

Therefore without limiting the invention to the construction shown and described or enumerating equivalents, I claim and desire 70 to secure by Letters Patent:—

1. A cross bar for rail anchors constructed with a jaw adapted to engage the rail base at one side, a shoulder adapted to engage the rail base edge at the opposite side 75 and curved surfaces upon the lower side of said bar below said shoulder adapted to engage and coact with a pressure producing part.

2. A rail gripping cross bar for rail stays 80 constructed with an integral base flange engaging jaw a transversely extending portion, and an integral rail base edge engaging portion at the end opposite said jaw, said transversely extending portion having convex surfaces on the lower side thereof adjacent the rail base edge engaging portion adapted to engage with a pressure producing part.

3. A vertical pressure producing part for 90 anticreepers constructed so to engage the upper surface of a rail base and a rail base edge and bottom engaging element that rotational movement of said pressure producing part about a longitudinal axis above the 95 rail base will force surfaces of said pressure producing part into engagement with surfaces of the bottom engaging element below the rail and thereby produce pressure of the bottom engaging element upwardly upon 100 the rail bottom.

4. A part for rail anchors constructed with surfaces adapted to engage a rail bottom engaging element below the rail and a portion adapted so to engage the upper 105 surface of the rail base flange as to permit angular movement of said part about a longitudinal axis above the rail base.

5. A rail stay comprising a rail gripping element engaging the rail base at one side 110 of the rail and a part so engaging said gripping element below the rail and the upper surface of the rail base opposite to said gripping element as to be rotatable about a longitudinal axis above the rail base for 115 effecting the gripping action of said element.

6. An anticreeping device for rails, comprising a cross bar engaging with the top and bottom of the base flange of the rail at 120 one side of the rail and with the edge and projecting above the base flange of the rail at the other side of the rail and a part constructed to engage with the upper surface of the rail base and the upwardly projecting edge engaging portion of the cross bar above the rail base and to be forced into engagement with the cross bar below the rail base.

7. A rail anchor, comprising a transverse 130

5 rail base flange engaging part and a tension member constructed so to engage the rail base and said base flange engaging part that transverse rotation of said member about the rail base will force said member into engagement with said part and draw said part into gripping engagement with the rail base flange and that longitudinal movement of the rail in relation to said member will 10 produce angular movement of said part and automatically increase the grip of the device upon the rail.

15 8. A rail anchor comprising a flange gripping and bottom engaging element and a vertical pressure producing part adapted so to engage the upper surface of the rail base and said flange gripping and bottom engaging element below the rail base that movement of the rail in relation to said 20 pressure producing part will produce angular movement of said flange gripping and bottom engaging element and thereby increase the grip upon the rail.

25 9. A device for preventing the creeping of rails, comprising a rail base gripping element transversely disposed in relation to the rail and a part so engaging the rail base and said element as to be rotatable in a plane transverse to the rail about an axis above 30 the rail.

35 10. A rail stay, comprising a transversely extending part engaging the top and edge of the rail foot flange at one side of the rail and the bottom and edge of the rail foot flange at the other side of the rail and a vertically extending part constructed to engage the transversely extending part below the rail and to have pivotal engagement with the upper surface of the rail base.

40 11. An anticreeper for rails comprising a transversely extending part engaging opposite edges of the rail base and the upper surface of the rail base at one side of the rail and a vertically extending element so engaging the upper surface of the rail base at the other side of the rail and said transversely extending part below the rail that transverse rotation of said vertically extending part about the rail base will cause said 45 transversely extending part to grip the rail base and that longitudinal movement of the rail in relation to said vertically extending part will produce angular movement of said transversely extending part and automatically increase the grip upon the rail.

55 12. A rail anchor, comprising a transversely extending part engaging the bottom, opposite edges and the upper surface of the rail base at one side of the rail and a vertically extending part constructed with a tie engaging portion having pivotal engagement with the upper surface of the rail base and with the transversely extending part below the rail.

60 13. A rail stay, comprising a bottom en-

gaging part constructed to bear upon the bottom of a rail and a vertical pressure producing part adapted so to engage the bottom engaging part and the upper surface of the rail base that said pressure producing part may be rotated transversely about a longitudinal axis above the rail base when being forced into position and, when in position, move angularly about a transverse axis.

75 14. An anticreeper for rails, comprising a bottom engaging cross bar and a pressure producing part constructed with tie engaging portions adapted so to engage the upper surface of the rail base that rotational movements of said pressure producing part about an axis above the rail base will force surfaces of said pressure producing part into engagement with said bottom engaging cross bar below the rail and thereby produce pressure of said bottom engaging cross bar upon the bottom of the rail and that longitudinal movement of the rail will produce angular movement of said cross bar and automatically increase the gripping action upon the rail.

80 15. A rail anchor, comprising a part engaging the top and edge of the rail base flange at one side of the rail extending underneath the rail and engaging the bottom and edge of the rail base flange at the other side of the rail and a key provided with means for engaging rotatably with the upper surface of the rail base and with means for engaging said part below the rail base 100 when said key is moved angularly in relation to the rail.

85 16. A rail stay, comprising a part engaging the bottom and opposite edges of the rail base flange and a vertical pressure producing member constructed to engage the upper surface of the rail base flange and to be forced into engagement with said part below the rail by rotation of said pressure producing member about an axis above the 110 rail base flange.

90 17. A rail anchor, comprising a rail base flange engaging and gripping element and a rail engaging device so engaging the rail above and said element below the rail base 115 as to permit angular movement of said device about a longitudinal axis above the rail base and about a transverse axis.

95 18. A rail stay, comprising a rail embracing and gripping part and a rail engaging pressure producing element having tie engaging portions so connected to said part as to be rotatable about an axis longitudinally disposed above the rail base and to permit angular movement of said element 120 about a vertically disposed axis.

100 19. A device for preventing the creeping of rails comprising a rail base gripping element transversely disposed in relation to the rail constructed to engage opposite edges 130

thereof and a tie-engaging part engaging the base flange and said gripping element above and the bottom of one end of said gripping element below the rail base.

5 20. A reversible anticreeper comprising a bar constructed to engage the upper surface of the base flange at one side of a rail and to engage and extend above the edge of the base flange at the other side of the rail
10 and a key constructed to engage the base flange and said bar above and the lower surface of said bar at one end below the rail and provided with reversely disposed tie-abutting portions.

15 21. In a rail anchor, the combination with a rail and a cross tie of a part engaging and gripping the base flange at one side of the rail extending underneath and engaging the edge of the base flange at the other side of
20 the rail and means engaging the tie and the base flange above and the end of said part below the rail base for holding said bar in engagement with the rail.

22. In a rail anchor, the combination of
25 a bar provided at one end with means for engaging and gripping the base flange of a rail and having the other end turned up to engage and project above the edge of the rail base flange and means engaging the base
30 flange and the upturned end of said bar above and the lower surface of said bar below the rail base for drawing the end of the bar up into contact with the rail bottom and for holding the end of the bar in spaced relation to a cross tie.

35 23. A rail anchor comprising a flange gripping and bottom engaging element and a vertical pressure producing part adapted

to engage a cross tie and to so engage the upper surface of a rail base and said flange gripping and bottom engaging element below the rail base that movement of the rail in relation to said pressure producing part will produce angular movement of said flange gripping element and thereby increase
40 the grip upon the rail.

24. An anticreeper comprising a bottom engaging part constructed to engage the bottom and opposite edges of a rail base and a tie-engaging vertical pressure producing part adapted so to engage the bottom engaging part and the upper surface of the rail base that said pressure producing part may be rotated transversely about a longitudinal axis above the rail base when being forced
45 into position and that longitudinal movement of the rail will produce angular movement of said pressure producing part about a transverse axis.

25. A rail stay comprising a rail base
50 flange engaging and gripping element and a rail engaging device provided with a tie abutment so engaging the rail above and said element below the rail base as to permit angular movement of said device about
55 a longitudinal axis above the rail base when being forced into position and to permit angular movement of said element about a vertical axis and of said device about a transverse axis, when in position upon the
60 rail.
